UNITED STATES PATENT OFFICE

ROBERT T. GALLAGHER, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

SHEARING MACHINE

Application filed November 21, 1928. Serial No. 320,950.

The present invention relates to that class of shearing machines which is employed for cutting up metal bars, billets, and other elongated products, while the same are in motion.

5 In one type of such shearing machines, the co-operating upper and lower shear blades, that are caused to approach each other in the performance of each cut, are carried in a frame or support that is capable of a limited swing-
 10 ing movement in the direction of travel of the material, so as to allow the shear blades to follow along with said material for the duration of each cutting operation. Following each such cutting operation, and the resump-
 15 tion by said blades of their normal separated relation, the frame or support must be re-
 turned to its initial stationary position, in readiness for the next cutting operation,— and it is the object of the present invention to
 20 provide mechanism for insuring a prompt and unfailing return movement under all conditions, with particular regard for the prevention of heavy blows or shocks, such as would cause damage to the machine, or produce re-
 25 bound or inaccurate positioning of the swing-
 ing frame. The above and other objects are attained by the mechanism hereinafter fully described in connection with the accompanying
 30 drawings, in which—

Fig. 1 is a front view of a shearing machine embodying the invention.

Fig. 2 is a central vertical sectional view, in the plane of the broken line 2—2, Fig. 1.

Fig. 3 is a detached perspective view of the
 35 actuating shaft of the machine.

Fig. 4 is a large scale fragmentary sec-
 tional view in the plane of the line 4—4,
 Fig. 1.

Fig. 5 is a fragmentary view of the ma-
 40 chine as seen in side elevation from the right
 hand side of Fig. 1.

Like reference characters refer to like
 parts in the different figures.

The machine provides the usual stationary
 45 base 1, having spaced upright standards 2, 2
 that provide at their upper ends suitable bear-
 ings for a rotatable shaft 3. Said shaft 3,
 just inwardly of its bearings in the standards
 50 2, 2, provides spaced matching eccentric por-
 tions 4, 4, and between said eccentric portions

4, 4, said shaft 3 provides an intermediate eccentric portion 5 that is diametrically op-
 posed to the portions 4, 4. Suitable eccentric
 straps 6, 6, surround the eccentrics 4, 4 and
 provide for the suspension therefrom of a
 55 frame 7 which, in consequence of its mount-
 ing on the shaft 3, is free to swing between
 the housing side or standards 2, 2.

Said frame 7, on the opposed inner surfaces
 60 of its vertical sides, provides ways or guides
 8 for the sliding movement of a head 9, the
 latter having a pivotal connection 10 with
 a member 11 whose upper portion is formed
 as an eccentric strap 12 in surrounding rela-
 65 tion to the central eccentric portion 5 of
 shaft 3. The head 9 carries an upper shear
 blade 13 adapted to cooperate with a lower
 shear blade 14 carried by the frame 7. The
 above described mechanism, of and by itself,
 70 forms no part of the present invention, be-
 ing in substance and in all essential respects
 the equivalent of the mechanism shown and
 described in Edwards Patent No. 1,047,185,
 dated December 17, 1912. In the operation
 75 of the above described mechanism, with the
 stock passing between the shear blades 13
 and 14 in the direction of the arrows A, Fig.
 2, a single revolution of the shaft 3 pro-
 cures a cut in the following manner:—

In the normal inoperative position of the
 parts shown in Fig. 2, the head 9 carrying
 upper blade 13 is at the top of its stroke,
 while the frame 7 carrying lower blade 14 is
 at the bottom of its stroke. Since the eccen-
 85 trics 4, 4 and 5 which carry the frame 7 and
 head 9, respectively, are one hundred and
 eighty degrees apart, the two shear blades
 13 and 14 will start to approach each other
 as soon as the shaft 3 begins to rotate. Such
 approach carries the blades into engagement
 with the moving stock, and as said blades
 cut into the stock, the carrying frame 7, be-
 ing pivotally suspended from the shaft 3,
 swings to the right in Fig. 2 with the move-
 90 ment of the stock, so that the completion of
 the cut occurs with the frame 7 substantially
 displaced to the right from the position
 shown in Fig. 2, whereby there is no substan-
 tial retardation of the travelling stock. Sub-
 95 stantially coincident with that part of the
 100

revolution of shaft 3 which again separates the blades 13 and 14, the frame 7, being no longer engaged with the travelling stock, is left free to swing back to its normal position shown in Fig. 2,—and it is with this return swing of frame 7 that the present invention is particularly concerned.

In order to provide a force which will be operative to secure such return movement, the outward swing of frame 7, under the influence of the travelling stock, is made to compress a pair of springs 15, 15; as shown in Figs. 1 and 2, a pair of brackets 16, 16, secured to the rear edges of the standards 2, 2, provide bearings for a shaft 17 to which is secured a pair of arms 18, 18, each connected to the rear side of frame 7 by a link 19. Other arms 20, 20, secured to shaft 17, have pivotal connection with vertical rods 21, 21 passing upwardly through the brackets 16, 16 and each encircled by one of the springs 15. Each spring 15 bears at its lower end on the associated bracket 16, and its upper end is engaged by an adjustable collar 22 on the associated rod 21. As the frame 7 is swung outwardly, by the engagement of the shear knives 13 and 14 with the travelling stock, the shaft 17, connected to said frame by arms 18, 18 and links 19, 19, rocks counterclockwise in Fig. 2 and thereby, through arms 20, draws the rods 21 downwardly, to compress the springs 15, 15 by downward movement of the collars 22, 22. Thus said springs are caused to store up energy, which, upon the completion of the cutting operation, is instantly available to procure the return swing of the frame 7 to its normal position, as illustrated in Fig. 2, where the rear side of said frame brings up against a pair of rollers 23, 23 provided by the base 1.

However, this return swing, as actuated by the springs 15, 15 is an uncontrolled movement and is likely to take place at such a speed as to impart a heavy blow on the mechanism, as well as to produce a rebound of the frame 7, so that its accurate registration with the normal rest position shown in Fig. 2 will be seriously disturbed. In order to eliminate these difficulties, this invention imposes a definite control on the speed or acceleration of said return swing, through the medium of a dash pot mechanism,—and to this end, the shaft 17 is extended through the bracket 16 on one side, as shown at 17', Figs. 1 and 4, and has secured thereto an arm 24. The angular movements of shaft 17 in response to the outward and return swings of the frame 7 are caused to produce rectilinear movements of a sliding crosshead 25, through the medium of a link 26, pivotally connected to said crosshead and to the arm 24.

As shown in Fig. 4, the dash pot cylinder 27 is secured to the side of the adjacent standard 2, and a piston or plunger 28 within said cylinder has its rod 29 projected through a

stuffing box in the head of the cylinder and secured to the adjacent end of the sliding crosshead 25. An extension 29' of the rod 29, on the opposite side of piston 28, operates as a guide to maintain the alinement of the parts. When the frame 7 swings forward, under the influence of the travelling stock, the piston 28 will travel freely toward the right in Fig. 4, owing to the fact that the wall of cylinder 27 provides an outlet port 30 at the right hand end for the free egress of the fluid, such as oil, with which the cylinder is maintained filled, as for instance from a supply pipe 31 that feeds a cylinder passage 32. An outwardly opening check valve 33 controls communication between the port 30 and a cylinder passage 34, the latter opening unrestrictedly to the left hand end of cylinder 27, so that the fluid displaced by the piston's right hand movement passes freely to the cylinder space on the left side of the piston. On the return swing of frame 7 however, no such free and unrestricted transfer of the fluid from one side to the other of the piston, can take place; the automatic closure of valve 33 prevents any flow back through passage 34 and port 30, so that the only escape for the fluid, on this left hand movement of piston 28, is through a restricted opening 35 connecting the left hand end of cylinder 27 with the passage 32. Said opening 35 is adjustable as to size by a needle valve 36; thus the rate at which the frame 7 can travel on its return swing is always under the control of the operator, because such rate is determined by the adjustment of the needle valve 36 to closely regulate the rate at which the fluid can pass back from the left hand end to the right hand end of cylinder 27. When the piston 28 is almost at the end of its left hand stroke, corresponding to the return swing of frame 7, the port 35 will be cut off by said piston, and from this point on, until the piston arrives at a position corresponding to the rest position of frame 7, the dash pot fluid seeps into port 35 through a depression or groove 37 of very restricted area, thus to further slow down the frame just before it comes to a full stop. In this way, the return swing of the frame is accomplished in the entire absence of any shock or rebound, and its exact registration with the rest position is always assured.

Just as the frame reaches said rest position, at the completion of a single revolution of shaft 3, it is desirable, though not necessary, to apply a braking force on said shaft, in order to prevent any over-run or displacement that might disturb the full open position of the shear knives 13 and 14. To this end, as best shown in Fig. 5, a brake band 38 is arranged in surrounding relation to an enlargement 3' of shaft 3, said band being anchored at 39 and having its other end pivotally secured to an arm 40 that is carried by a rock shaft 41. At the commencement of

each cutting operation, a solenoid 42 is energized in any suitable way, in consequence of which an arm 43, connecting said rock shaft 41 with the movable member of said solenoid, is raised, thereby to rock the shaft clockwise in Fig. 5 and thereby, through an arm 44, to release the brake band 38 from the closing or contracting force of a spring 45. This permits a single revolution of the shaft 3 to take place, with the brake band 38 free, but as soon as such single revolution is completed, the solenoid circuit is broken and thereupon the spring 45 becomes effective to draw the band 38 tight around the enlargement 3' of shaft 3, thereby to hold said shaft stationary until the next cut is initiated.

I claim,

1. In a shearing machine of the class described, a frame in which the shear blades are carried, said frame being mounted for movement in unison with the material during each cutting operation of said blades, an adjustably-mounted spring, linkage between said spring and said frame, whereby the force of said spring is effective to secure the return of said frame, after each cutting operation, to its initial position of rest, and a dash pot mechanism acting through said linkage to oppose the action of said spring on the return movement of said frame.

2. In a shearing machine, an actuating shaft, a knife-carrying frame hung from said shaft and adapted to swing in the direction of travel of the material during each cutting operation, as effected by a single revolution of said shaft, spring means to insure return of said frame to its initial position of rest after each cutting operation, a dash pot to control the speed of such return movement, and braking means made operative on said shaft at the end of such return movement, to hold said shaft stationary until the next succeeding cut is initiated.

3. In a shearing machine, an actuating shaft, a blade-carrying frame having a pivotal mounting on said shaft to permit, at each cutting operation, a movement of the frame with the material and a return movement to rest position, a dash pot to control the speed of such return movement, and braking means made operative on said shaft at the end of such return movement, to hold said frame in rest position.

Dated this nineteenth day of November,
55 1928.

ROBERT T. GALLAGHER.
